UNITED STATES PATENT OFFICE.

ALBERT W. METZNER, OF DAYTON, OHIO, ASSIGNOR TO THE STANDARD REGISTER COMPANY, OF DAYTON, OHIO, A CORPORATION OF OHIO.

AUTOGRAPHIC REGISTER.

1,394,436.

Specification of Letters Patent.

Patented Oct. 18, 1921.

Application filed July 8, 1919. Serial No. 309,336.

To all whom it may concern:

Be it known that I, ALBERT W. METZNER, a citizen of the United States, and a resident of the city of Dayton, in the county of 5 Montgomery and State of Ohio, have invented certain new and useful Improvements in Autographic Registers, of which the following is a full, clear, and exact description, reference being had to the accompanying drawings, forming a part of 10 this specification.

My invention relates to autographic registers wherein duplicate strips are fed over a tablet plate and like impressions made 15 upon each strip by the operator writing on the top strip, and carbon paper transferring his written matter to the sheets beneath.

In machines of this type, it is not always 20 desirable that the strips should be fed out in equal amounts, at every operation of the machine. One instance of this is where the machine is used for billing goods to customers, where the owner desires some sort of 25 shipping label to go on the goods. In such a case, it can readily be observed that the use of a special strip of paper in connection with the regular strips, together with a different amount of feed for the special strip, 30 would provide a device which could be used for duplicating merely the address portion of the regular strips on the special strip.

Another instance where this different feed would be of value is for the advancing 35 of a summary strip in recording autographic registers, and various other uses might suggest themselves, in connection with autographic registers and the like, wherein the feeding of one of a series of strips is made 40 at a different rate from the others, although all the strips receive a similar autographic imprint.

It is also a necessity to provide some 45 transfer means which will serve to prevent the special strips of paper from receiving all of the impressions made on the regular full length sections, because otherwise the device would be of no value for some purposes.

50 It is the object of my invention to provide a feed for autographic register paper which is of the type above mentioned, and

this object I accomplish by that certain construction and arrangement of parts to be hereinafter more specifically pointed out 55 and claimed.

In the drawings,

Figure 1 is a detail perspective of the feeding mechanism.

Fig. 2 is a view showing the regular and 60 special strips in a billing machine.

Fig. 3 is a detail side elevation of the mutilated one of the feeding sprockets.

Fig. 4 is a perspective of a modified form 65 of the device.

Fig. 5 is a detail rear elevation of the feed device.

The paper employed in the machine where billing machines are used comprises the usual strips A and the special strip B. The 70 special strip B is made up in the form preferably of headings along with the spaces for receiving the addresses of the consignees, omitting the balance of the spaces, printing or what not that appear on the remaining 75 strips. When strip B is issued from the machine it is intended that one section of this strip shall issue with each regular sized section of strip A, thereby providing, with strip B, for address tags, which can be secured to the package forming the article 80 which is to be consigned.

Since a sprocket feed is employed in the device chosen to illustrate my invention, it becomes apparent that either the perforations for strip B or the number of pins on the feeding sprockets or both must be modified so far as this strip is concerned. The feeding device comprises preferably the rotary members 1 and 2 on the shaft 3, of 90 which the member 1 is of the ordinary type to be found in sprocket feed registers, and is equipped with the usual uniformly spaced, successive teeth 4. The member 2 is mutilated, in that it has the sprocket teeth removed except for a limited number, as shown at 5. The regular paper A has the marginal perforations 6, spaced to correspond with the spacing of the teeth, located along each side thereof, whereas the special strip 100 B has marginal perforations 7 along one side only, and this strip is reduced in width, compared to the strip A.

In another form of the device, the nor-

mal length paper C has the marginal perforations 6^a, along one side thereof to engage the complete sprocket, while the special strip B is the same as before and engages 5 the mutilated sprocket only (see Figs. 4 and 5).

It can readily be observed that when the strips are set over the feeding sprockets, with the strips A in mesh with teeth on both 10 sprockets, and the strip B with its perforations in mesh with those on the mutilated sprocket only, that the result of one rotation of the sprockets will be to feed the strips A out of the register in one full sized section, 15 and that the special strip will only feed an amount determined by the number of sprocket pins left upon the mutilated sprocket.

As the pins on one side are sufficient to 20 carry the strips A out of the machine, the machine can be relied upon to perform its normal work. The strip B, however, is moved forward only a definitely limited amount, which will, of course, be made to 25 correspond with the amount of space necessary to allow for each bill head. Where the strips A are used, there is a partial engagement by the mutilated sprocket, this not being true for the strip C (Figs. 4 and 5). But 30 the chief function of the mutilated sprocket in the case of full length strips is to preserve or readjust alinement, and its use can be dispensed with as far as the normal length strips are concerned, as has been done in the 35 device shown in Figs. 4 and 5, because so far as feeding is concerned it is not necessary. Also the device of this modified nature is better from the point of view of chance tearing of the normal length strips when they are 40 suddenly engaged by the mutilated sprocket in the first described structure, while in the act of being fed by the complete sprocket.

In order to illustrate the means preferably adopted by me to prevent the registrations 45 made upon the full length sections from being transferred *in toto* to the special strip, I have shown in outline the parts of an autographic register. There is thus the casing 10 and the usual tablet plate 11, which is mounted in any desired manner in the casing. The 50 shaft 3 for the two sprocket members is mounted in the frame in any desired manner, and alongside of the tablet plate is the usual box 12 for carbon paper strips 13.

It is possible for me to supply special carbon paper for use in connection with the above described machine, although this would mean a departure from standard practice. Thus in a machine employing two 60 strips with full length sections and two special strips of paper having smaller sections, the carbon paper roll would have to have one full width and two half width pieces of carbon paper rolled together for installation 65 in the carbon paper box. If there was but

one special length piece, then but one special width carbon paper would have to be provided.

I am also able to make suitable provision for this feature by using in addition to the usual tablet plate 11 an additional plate or shield 14, which is made of thin metal preferably, and is merely placed in between the carbon paper and the special strip, at the point where no registrations are to be transferred. Sufficient support for the shield plate is provided by the sides of the machine casing, and no special means of holding it in place are considered necessary.

While I have above referred to one full 80 sized sheet and one special sheet, it is not to be understood that I thereby limit myself in any way, since the number of regular and the number of special strips has nothing to do with the invention herein.

In some instances, in order to provide for a "backlash" preventer for the strips engaged by the mutilated sprocket, I have found it desirable and practical to mount on the casing of the machine a spring fork 9 90 which straddles the mutilated sprocket and holds the special strip steady when the pins 5 are just entering or just leaving the perforations of the strip.

So far as I am advised, I do not know of 95 any instance in which there are strips of different sizes fed out of an autographic register at the same feeding operation, nor am I aware of any instance where the same feeding device has been employed for simultaneously feeding two strips of paper an unequal distance over a tablet plate in an autographic register.

Both these functions are accomplished by the mechanism I have now described, and furthermore the feeding devices have the further characteristic of retaining or automatically adjusting the various strips of paper in perfect alinement with each other.

It has not been thought necessary to describe in detail nor to show in the drawings a complete autographic register since the frame or casing, the means for installing the paper, the tablet plate, feeding orifice, tearing blade, operating handle and the like are 115 all familiar in the art, and may be varied in detail as desired in connection with my invention.

Having thus described my invention, what I claim as new and desire to secure by Letters Patent, is:

1. In an autographic register, a pair of pin bearing rotary bodies for feeding a plurality of marginally perforated strips of paper, one of said bodies having a desired portion thereof free from pins and the other having successive equally spaced pins, said pins being spaced to enter the marginal perforations in said strips of paper, and means for preventing slippage of papers having 125 130

one margin out of pin engagement when freed from engagement with the limited number of pins.

2. In an autographic register, a pair of interconnected and simultaneously rotated pin bearing bodies for feeding a plurality of strips of marginally perforated paper in alinement with each other, both of said bodies being adapted to engage some of the strips, and one of the said bodies being the sole engaging member for one of the strips, said one of the pin bearing bodies having a portion of its periphery free of pins, and the remaining pins thereon being alined and 15 equally spaced to the pins on the other body.

3. In an autographic register, a feeding device for perforated paper comprising a pair of interconnected sprocket elements, means for rotating them simultaneously, one 20 of said elements having equally interspaced teeth, and the other having similarly spaced teeth, covering part of its periphery only, for the purpose described.

4. In an autographic register having strips 25 of paper, and having some strips perforated on one edge and some on the other, rotating pin bearing bodies for engaging said perforations interconnected with each other, and bearing equally spaced pins, but said pins 30 covering different amounts of space on the said rotating bodies.

5. In an autographic register, a feeding device for moving a plurality of films of paper over a writing surface, and then issuing 35 them from the machine, and means in connection with said feeding device for feeding different sized sections simultaneously, and means for blocking off the trans-

fer of selected portions of the imprints on the larger sized sections from the smaller 40 sections.

6. In an autographic register, a feeding device for moving a plurality of films of paper over a writing surface, and then issuing them from the machine, and means in connection with said feeding device for feeding different sized sections simultaneously, and means for confining the transfer of imprints on the larger sized sections to selected imprints for the smaller sections, comprising 45 a shield mounted over the writing surface to prevent the operation of the usual carbon paper.

7. In an autographic register, a feeding device for perforated paper comprising a 55 pair of interconnected sprocket elements means for rotating them simultaneously, one of said elements, having equally interspaced teeth, and the other having similarly spaced teeth, covering part of its periphery only, 60 and means for preventing slippage of paper when freed from engagement with the element having teeth on a part only of its periphery.

8. In an autographic register, a feeding 65 device for perforated paper comprising a pair of interconnected sprocket elements, means for rotating them simultaneously, one of said elements having equally inter-spaced teeth and the other having similarly 70 spaced teeth covering part of its periphery only, but alined with the corresponding teeth on the other element, for the purpose described.

ALBERT W. METZNER.
